UNITED STATES PATENT OFFICE.

WILLIAM H. LOGAN AND JOHN NIELSON, OF BANDON, OREGON.

BUOY-COUPING.

1,173,820.

Specification of Letters Patent. Patented Feb. 29, 1916.

Application filed September 1, 1915. Serial No. 48,494.

To all whom it may concern:

Be it known that we, WILLIAM H. LOGAN and JOHN NIELSON, citizens of the United States, residing at Bandon, in the county of 5 Coos and State of Oregon, have invented new and useful Improvements in Buoy-Couplings, of which the following is a specification.

This invention relates to couplings for 10 marine buoys and it consists in the novel features hereinafter described and claimed.

An object of the invention is to provide a 15 coupling of simple and durable structure adapted to be applied to a floating buoy for the purpose of connecting the same with the cable or anchor chain.

Heretofore it has been the practice to form 20 an eye at the head of the buoy, and this eye is caught through the terminal link of the cable chain, but owing to the weight of the chain and the constant movement of the buoy in the water, the eye eventually wears through and the chain is frequently lost. Even if the chain is retained, it is necessary 25 at frequent intervals to lift the buoy, disconnect the chain from the eye, and place a new head with a new eye upon the buoy in lieu of the head and eye removed. This involves considerable expense, and it is the 30 object of the present invention to provide a device which may be easily and quickly applied to the head of a buoy for the purpose of connecting the cable chain with the same, thereby reducing the expense in replacing 35 the said parts after they have been worn and become unfit for service.

With the above objects in view the device 40 consists in its preferred form in providing an annular groove at the side of the head of the buoy, and hooks provided at their shanks with flanges are applied to the sides of the head of the buoy. The flanges upon the shanks are seated in the groove and a ring surrounds the shank and is securely held in 45 position by a cross bar which passes through the shanks of the hooks and bears at an edge against one edge of the ring. The hooks are provided with overlapping bills which are passed through the terminal link of the cable 50 chain. The bills are provided at their ends with lugs and the shanks are provided at their sides with recesses. The lug upon the bill of one hook is located in the recess at the shank of the other hook and consequently the terminal link of the cable chain 55 is securely held with relation to the buoy.

In the accompanying drawings: Figure 1 is a side elevation of the lower part of a buoy showing the coupling applied thereto. Fig. 2 is a sectional view of the same. Fig. 3 60 is a side elevation of one of the hooks. Fig. 4 is similar view looking at the hook at a right angle to the view shown in Fig. 3. Fig. 5 is a sectional view of a slightly modified form of the coupling. Fig. 6 is a transverse 65 sectional view of the form shown in Fig. 5.

As shown in the accompanying drawings, the buoy 1 is provided with a head 2 which in turn is surrounded at its side by an annular groove 3. Hooks 4 are located at the opposite side portions of the head 2, and the said hooks are provided at the upper edges of the shanks 5 with flanges 6, which lie in the groove 3. The bill ends 7 of the hooks overlap each other, and the end of one hook 70 extends up within the inner portion of the shank of the other hook, and vice versa.

The bill of each hook is provided at its end with an outstanding lug 8 and the shanks 5 of the hooks are provided at their 80 inner sides with recesses 9, which receive the said lug. A band 10 surrounds the upper ends of the shanks 5 of the hooks and hold the flanges 6 in position in the groove 3. A wedge-shaped bar 11 passes transversely through the upper portions of the shanks 5 of the hooks 4, and the lower edge of the band 10 has contact or bears against the upper edge of the said bar. A cotter 85 pin 12 passes through the smaller end portion of the bar 11, and is located beyond the outer surface of the shank of one of the hooks 4 and holds the said bar in position 90 in the shanks. The terminal link 13 of a cable chain receives the bills 7 of the hooks 95 4, consequently the said hooks serve as means for coupling the cable chain to the buoy 1.

In the form of the invention as shown in Figs. 5 and 6 the shanks 5 of the hooks 4 100 are secured to the head 2 by means of rivets 14, and in this form the said head is devoid of the annular groove 3 hereinbefore described in conjunction with the form shown in Fig. 1. The band 10 in the modified 105 form of the invention surrounds the shanks 5 and covers the outer ends of the rivets or studs 14.

The form of the invention as shown in Fig. 1 of the drawings, is employed when 110 the buoys are put out new with the specific form of coupling means attached thereto.

In the event that a buoy has to be removed from the water for repairs the form of the invention as shown in Figs. 5 and 6 is employed, wherein the shanks of the hooks are secured to the head of the buoy by means of the rivets or studs, and the ring 10 is placed about the shanks in a manner to cover the outer ends of the said rivets or studs.

While the coupling is described as a buoy attachment it will be understood that it may be used to advantage for connecting an anchor with a cable chain without departing from the spirit of the invention.

Having described the invention what is claimed is:—

1. In combination with a buoy, hooks applied to the head thereof and having overlapping bill ends one hook adapted to support the bill of the other hook.
2. In combination with a buoy, hooks applied to the head thereof, and provided with recesses, said hooks having their bill ends overlapping each other, each hook having a lug which enters the recess of the other hook.
3. In combination with a buoy, hooks ap-

plied to the head thereof and provided with recesses, said hooks having their bill ends overlapping each other, each hook having at the end of its bill a lug which enters the recess of the other hook.

4. In combination with a buoy having a circular head, hooks having semi-circular shanks applied to the said head, the bill ends of the hooks overlapping each other.

5. In combination with a buoy, hooks having shanks applied to the head thereof, the bill ends of the hooks overlapping each other, a ring surrounding the shanks of the hooks, and a bar passing through the shanks of the hooks and bearing against the ring.

6. In combination with a buoy having a head provided with a groove, hooks having shanks provided with flanges which lie in the groove of the head and means for holding the shanks against the head.

In testimony whereof we affix our signatures in presence of two witnesses.

WILLIAM H. LOGAN.
JOHN NIELSON.
